Charles S. Baron,
Inventor;

By Joseph F. Schling,
Atty.

UNITED STATES PATENT OFFICE.

CHARLES S. BARON, OF TIFFIN, OHIO.

LIQUID-CONTAINER PROVIDED WITH REMOVABLE HINGED TOP.

1,375,993.

Specification of Letters Patent. Patented Apr. 26, 1921.

Application filed July 9, 1919. Serial No. 309,580.

To all whom it may concern:

Be it known that I, CHARLES S. BARON, a citizen of the United States of America, residing in the city of Tiffin, in the county of Seneca, in the State of Ohio, have invented certain new and useful Improvements in Liquid-Containers Provided with Removable Hinged Tops, of which the following is a specification, reference being had to the accompanying drawing.

The object of my invention is to produce improvements in containers provided with removable hinged tops, and specifically in molasses jugs of that description wherein provision is made for the entire removal of the top at will, and for conveniently, with increased security of union, attaching the top to the container.

What constitutes my invention will be hereinafter specified in detail and succinctly set forth in the appended claim.

In the accompanying drawing,

Figure I is a side elevation of the upper portion of a molasses jug with its top secured thereto in place and closed.

Fig. II is a top plan view of the subject matter of Fig. I.

Fig. III is a section on the line III—III of Fig. I.

Fig. IV is a figure corresponding to Fig. III, illustrative of curvilinear contours in cross section in place of the plane contours shown in Fig. III.

Referring to the numerals on the drawing, 35 1 indicates the body of a container which may be made of any suitable or preferred shape and dimensions and of any preferred material, glass or fictile material being that which is usually employed.

40 2 indicates the handle thereof, which preferably embodies a transverse projection 3 extending from the rear of the body 1 and whose upper surface 4 is preferably flush with the open mouth 5 of the body 1.

45 By aid of the projection 3, I secure to the top of the container a portion 6 of a metallic top which, in use, is fixed to the body 1. To it, as by means of a pintle 7 and knuckles 8 and 9, is hinged the movable part 10 of the top. A spring 11, preferably coiled about the pintle 7 and interposed between the upper surface of the top 6 and the bottom of

a thumb-piece 12, serves to keep the hinged portion 10 normally closed.

The members, so far above described, are 55 well known in the art and may be varied at preference.

My invention relates to the means by which the part 6 is secured to the body of the container. Such means consist preferably of a tail-piece 15 extending rearwardly from the part 6 of the top above and in close juxtaposition to the upper surface 4 of the projection 3. Depending from the tail-piece 15, upon opposite sides thereof, are resilient 60 cheek-plates 16 and 17, which, by their resiliency, tend to approach each other and thereby to constitute a clip. They terminate in lips 18 and 19, respectively.

The projection 3 is provided, as shown in 70 Fig. III, with upwardly convergent plane faces 20 and 21, and with downwardly convergent plane faces 22 and 23. The faces 22 and 20, and 23 and 21, respectively, meet at angles disposed to correspond substantially to the disposition of the angles at which the cheek-plates and their lips, respectively, meet.

The construction above described comprehends essentially oppositely disposed wedges, 80 the upper one being formed by the faces 20 and 21 and the lower one by the faces 22 and 23.

By my invention, the transverse extent of the narrow end of the upper wedge is 85 substantially equal to or a little less than the normal distance between the edges of the lips 18 and 19,—that is, when the top is separated from the container. Consequently, whenever it is desired to apply the 90 top to the container, it is only necessary to present the open lips 18 and 19 against the upper wedge, and then, by pressure applied to the tail-piece from above, to force the cheek-plates 16 and 17 into position upon 95 the projection 3. The application of pressure in the manner described causes the upper wedge above indicated, to separate the lips 18 and 19. As soon as the edges of the lips pass the angles in which the faces 20 and 22, and 21 and 23, respectively, meet, they snap into place and secure the tail-piece 15 to the body of the container.

The faces 22 and 23 are disposed at a com-

paratively obtuse angle relatively to each other, with the effect, in consequence of the resiliency of the cheek-plates 16 and 17, of drawing the tail-piece 15 snugly against the 5 top of the projection 3. Likewise, the lower wedge defined by the faces 22 and 23 serves to facilitate, upon the application of sufficient uplift pressure upon the tail-piece 15, the removal of the top 6 from the body 1.

10 It will be observed that the operation of attaching the tail-piece to the projection 3 and of detaching it therefrom, is accomplished by a wedging action, in each instance, that eliminates the necessity of direct manipulation of the cheek-plates 16 and 17, or either of them.

15 It is obvious that both or either of the wedging operations above described can be obtained through the employment of a variety of cross sectional contours of the projection 3, and the substitution of curvilinear contours for the plane faces previously described is shown, by way of example, in Fig. IV.

20 The projection 3 is shown as provided with shoulders at opposite ends of the cheek-plates 16 and 17, respectively, but this construction is nonessential, it being found in practice that a secure and stable union 25 between the parts 1 and 6 is obtainable 30 through the employment only of the com-

plementary cheek-plates and lips, and the projection 3 of corresponding cross-sectional contour as above specified.

35 What I claim is:

The combination with an open-mouthed container, provided upon one side thereof with a projection having a cross-sectional contour defined by respective pairs of lateral faces upwardly convergent to the top 40 of the member from medial points and downwardly convergent from said points, constituting oppositely acting wedges, of a top provided with a spring clip member detachably fitting over said projection, said member having resilient cheek-plates terminating in lips adapted to engage and to be moved apart by said wedges when the clip member is applied to and removed from said projection, the distance between the 45 pair of upwardly converging lateral faces at the top of the projection being less than the normal distance between the lips of the cheek-plates.

50 In testimony whereof, I have hereunto set 55 my hand in the presence of two subscribing witnesses.

CHARLES S. BARON.
